UNITED STATES PATENT OFFICE.

WILLIAM J. CASSITY, OF GUTHRIE, OKLAHOMA.

STUMP-BURNER.

1,126,388.

Specification of Letters Patent.

Patented Jan. 26, 1915.

Application filed March 10, 1914. Serial No. 823,781.

To all whom it may concern:

Be it known that I, WILLIAM J. CASSITY, a single man, a citizen of the United States, residing at Guthrie, in the county of Logan 5 and State of Oklahoma, have invented new and useful Improvements in Stump-Burners, of which the following is a specification.

The invention is primarily intended to provide novel means for removing stumps 10 by fire when clearing land for agricultural purposes.

The invention provides an appliance which is portable, economical in construction and effective in use, the same serving 15 to remove both seasoned and green or unseasoned stumps by fire.

The invention consists of a hollow body or casing adapted to be placed over the stump to be consumed, said casing resting 20 upon the ground and being provided with a removable top and draft inlets and smoke outlet.

The invention consists of the novel features, details of construction and combination of parts, which hereinafter will be more particularly set forth, illustrated and claimed.

In the drawings hereto attached:—Figure 1 is a perspective view of a stump burner 30 embodying the invention. Fig. 2 is a vertical central section.

Corresponding and like parts are referred to in the following description and indicated in all the views of the drawing, by 35 the same reference characters.

The body or casing 1 is preferably constructed of sheet metal and is of a shape and size to completely envelop the usual stump. The casing may have any outline and as 40 shown is preferably of frusto-conical shape to conform approximately to the outline of a stump. The bottom of the casing is open and in practice is adapted to be closed by the ground upon which the burner is placed, 45 earth being packed around the lower end of the casing to completely close the same. The top of the casing or hollow body is closed by means of a cover 2 which comprises a top and a depending rim. An 50 opening 3 is formed in the top of the cover 2 and is adapted to be closed by means of a slide 4 which is mounted in suitable ways or guides. A pipe 5 is removably fitted in the opening 3 and is suspended from the 55 top of the cover and extends within the

body or casing to within a short distance of the lower end thereof. The pipe 5 provides an inlet for air when the burner is used for consuming green or unseasoned stumps so as to convey the air to the roots to insure 60 combustion thereof. The slide 4 may serve to regulate the draft through the pipe 5 and also closes the opening 3 when the pipe 5 is removed and not required for immediate use. A smoke pipe 6 connects with the 65 lower portion of the body or casing 1 and carries off the products of combustion when the device is in service. Draft openings 7 are provided in the lower portion of the body or casing 1 and are adapted to be regulated by means of a damper 8 which is slidably mounted in ways or guides.

When the device is used for burning seasoned stumps the pipe 5 is removed and the opening 3 is closed by means of the slide 4. 75 The body or casing is placed over the stump to be burned and the cover 2 is placed in position. Kindling is placed within the body or casing at the base of the stump and is lighted, after which the damper 8 is 80 moved to uncover the draft openings. The stump having been lighted is gradually consumed, after which the device is removed and again placed in position for burning another stump. In the event of the stump being 85 green the roots are consumed after the body of the stump has been burned by placing the pipe 5 in position and closing the damper 8 thereby causing the draft to enter the pipe 5 and be delivered directly upon 90 the roots which are thus consumed.

From the foregoing description, taken in connection with the accompanying drawing the advantages of the construction and of the method of operation will be readily apparent to those skilled in the art to which the invention appertains, and while I have described the principle of operation of the invention, together with the device which I now consider to be the best embodiment 95 thereof, I desire to have it understood that the device shown is merely illustrative, and that such changes may be made when desired as are within the scope of the invention as claimed.

Having thus described the invention, what is claimed as new is:—

A stump burner comprising a casing of frusto-conical shape, the same having a draft opening therein, a damper for con- 110

trolling said draft opening, a smoke pipe connected with the lower portion of the casing, a cover closing the top of the casing having an opening therein to one side of a central point, a draft pipe fitting in said opening and a slide for closing the opening in the cover, the draft opening, inlet of said smoke pipe, and outlet of said draft pipe

being in alinement in close proximity to the lower edge of the casing. 10

In testimony whereof I affix my signature in presence of two witnesses.

WILLIAM J. CASSITY.
